UNITED STATES PATENT OFFICE.

PHILLIP F. BOYNTON, OF YONKERS, NEW YORK, ASSIGNOR TO HELBURN THOMPSON COMPANY, OF SALEM, MASSACHUSETTS, A CORPORATION OF MASSACHUSETTS.

DESIGN FOR LEATHER, SKIN, HIDE, IMITATION LEATHER, OR ARTICLE OF SIMILAR NATURE.

Application filed January 26, 1923. Serial No. 4,996. Term of patent 3½ years.

To all whom it may concern:

Be it known that I, PHILLIP F. BOYNTON, a citizen of the United States of America, residing at Yonkers, New York, have invented a new, original, and ornamental Design for Leather, Skins, Hides, Imitation Leather, or Articles of a Similar Nature, of which the following is a specification, reference being had to the accompanying drawing, forming a part thereof.

In said drawing, the figure is a plan view of a sheet of leather showing my new design.

I claim:

The ornamental design for leather, skin, hide, imitation leather or article of a similar nature substantially as shown.

Signed by me at city, State and county of New York, this 24th day of January, 1923.

P. F. BOYNTON.
